UNITED STATES PATENT OFFICE.

WILLIAM JUDSON MADDOX, OF JAMESTOWN, NEW YORK.

SANDING, ABRADING, OR POLISHING MACHINE.

No. 878,649.

Specification of Letters Patent.

Patented Feb. 11, 1908.

Application filed August 19, 1907. Serial No. 389,269.

To all whom it may concern:

Be it known that I, WILLIAM JUDSON MADDOX, of Jamestown, in the county of Chautauqua, State of New York, have invented a certain new and useful Improvement in Sanding, Abrading, or Polishing Machines; and I do hereby declare the following to be a full, clear, and exact description of the same, reference being had to the accompanying drawings, forming a part of this specification, and to the figures and letters of reference marked thereon.

This invention relates to machines for sanding, smoothing or polishing plane or substantially plane surfaces, such, for instance, as table tops, the invention being more particularly applicable in machines of that type wherein an abrading or sanding material is carried by an endless belt running on suitable pulleys and having means for pressing the belt into contact with the work intermediate the supporting pulleys.

In accordance with the present invention the means for pressing the belt into contact with the work is substantially arc shaped or in the form of a rocker with a long radius and mechanical means are employed for oscillating the presser or rocker so as to give a uniform action over a large area while the surface in contact with the belt at any one time is relatively small, such oscillatory movements, however, being under the direct control of the attendant whereby the range of movement, as well as the center of the arc of oscillatory or rocking motion may be varied at will or as required by the shape or contour of the work.

In the accompanying drawings: Figure 1 is a perspective view looking at the front side 40 of a machine embodying the present invention. Fig. 2 is a similar view looking down on a machine from which the abrading or sanding belt and work support have been removed. Fig. 3 is a sectional elevation 45 showing the link motion for the rocker shafts. Fig. 4 is a top plan of the parts shown in Fig. 3. Fig. 5 is a section through the bed of the machine with the rocker carrying frame in elevation but with the rocker or belt pressing member and its supports omitted. Fig. 6 is a detail perspective view of the carrying frame shown in elevation in Fig. 5. Fig. 7 is a detail perspective view of the preferred form of rocker shaft and mechanism for adjusting the center of the arc of oscillation of the rocker.

Similar letters of reference in the several figures indicate the same parts.

Inasmuch as machines of the type to which the present invention relates and employing an endless abrading belt, are already known, it will not be necessary herein to describe in detail the general construction of the machine further than to say that in the particular machine illustrated the bed composed of parallel members 1 is supported at the ends on hollow pedestals or legs 2, which may be suitably secured to the floor. Pulleys or carrying wheels 3 for the endless abrading belt 4 are mounted on shafts 5, 60 journaled in bearings at the ends of the bed. One of the shafts 5 carries fast and loose driving pulleys 6 or other appropriate driving means, while the other shaft is adjustable bodily by a hand wheel 7 to increase or reduce the tension on the belt and also about a vertical axis by hand wheel 8 to bring the shafts into parallelism, and the pulleys into a coincident plane, these adjustments being 65 well understood in this type of machine. 80

Horizontal tracks 9 for a sliding or rolling work support 10 are adjustably mounted on ways on the inner faces of the pedestals or legs, the adjusting means preferably consisting of vertically arranged screws 11 journaled 85 in the pedestals and having miter gears 12 at the upper ends with which similar but smaller gears 13 on a horizontal shaft 14 mesh. The shaft is adapted to be turned by a hand wheel 15, whereby the attendant may readily raise 90 and lower the work support and work thereon. The lower reach of the abrading belt passes above and substantially parallel with the top of the work support and in accordance with the present invention, a curved 95 presser or rocker 16 is employed to press the belt into contact with the surface of the work on the support. At or near its ends, the rocker 16 is connected by universal joints 17, which permit it to conform to the plane 100 of the face of the work, with the ends of lever arms 18 pivotally mounted at their proximate ends on a bracket or projection 20 on the front of the bed 1.

The lever arms are provided with slot 105 bearings 21 preferably extending substantially horizontally and adapted for the reception of pins 22 of crank arms 23 on the forward ends of rock shafts 24. The crank arms 23 are connected for simultaneous 110 movement by a link 25, best seen in Fig. 6, said link being bowed downwardly to pass

under the bracket 20 as shown and is preferably of such length that the crank pins are closer together than the centers of the rock shafts, with the result that oscillatory movement of the rock shafts will impart a rocking movement to the rocker 16, the relation of the parts and curvature of the rocker being such that during a full maximum movement each part of the face of the rocker is effective in pressing the belt against the work and hence while but a short section of belt is in contact at any one time the working area may be practically coextensive with the length of the rocker.

By varying the range of movement of the rocker and making the center of movement central of the area of the work to be operated on, it will be seen that the attendant has a perfect control, enabling him to dress small or large surfaces without lost motion or to dress slight depressions in the surface without removing an excessive depth of material at the high points, this being especially advantageous in dressing veneer or other thin coverings.

The rocker is operated and the manual control effected by a link drive, thus a rod 25 connects a crank arm 26 on the right hand rock shaft 24 with a slide 27 working in ways 30 in a cross piece 28 of the frame. The slide 27 is pivotally and slidably connected with a link 29 by a connection 30 (Fig. 3). The link 29 is pivotally mounted on a radius bar 31, the radial position of which is controlled 35 by a rack 32 and screw 33, on a shaft 34, journaled in the frame and having a hand wheel 35, said link being operated by a connecting rod 36 extending from one end of the link to a crank pin 37 preferably mounted in 40 the face of a screw gear 38, mounted on a shaft 39 journaled in the frame and also serving as the axis for the radius rod or bar 31. Gear 38 meshes with a screw or worm 40 on the drive shaft. Obviously, through the 45 manipulation of the hand wheel the link may be set to gear the rock shaft and rocker a long or short stroke or the movement of the rocker may be entirely arrested if the link be moved until its axis coincides with the center 50 of the connection between the link and slide.

The center of the arc of oscillation of the rocker may be most conveniently adjusted by adjusting the relative position of the crank arms on the rock shaft and as shown in detail in Figs. 6 and 7 it will be seen that the hub of the crank arm 26 is journaled on a sleeve 41, slidably mounted on the rock shaft 24. The crank arm is held against movement longitudinally of the shaft by a bracket 55 or key 42 entering a groove in the hub of the arm and its angular position with relation to the sleeve is controlled by a spiral slot 43 in the sleeve and a cooperating pin 44 in the hub of arm 26. The sleeve is moved longitudinally and its angular relation to the shaft

is preserved by a transverse slide nut or key 45, carried by the sleeve and working in a slot 46 in the shaft 24. The shaft is hollow for a portion at least of its length and receives a screw shaft 47 for co-operation with the nut 70 slide 45, said screw being held against longitudinal movement by a key 48 or other well known means and having at its end a hand wheel 49 for convenient manual manipulation. With this arrangement the center 75 of the arc of oscillation of the rocker may be shifted to any desired point without stopping the machine.

In the present machine the pressure exerted by the rocker is controlled in a very 80 simple manner by mounting the rock shafts in a supplemental frame 50 hinged at 51 (Fig. 5) to the rear of the main frame or bed and an adjustable stop screw 52 at the front of the supplemental frame adapted to rest on a 85 pivoted incline or cam plate 53 on the bracket 20. Said cam plate has a handle 54 whereby the downward limit of movement of the supplemental frame and rocker may be accurately adjusted and regulated in accordance 90 with the work to be done.

The weight of the supplemental frame may be and preferably is counterbalanced in part or to any desired extent by a counter-weight 55 adjustably mounted on the lever 95 arm 56, the forward end of said arm serving as a handle whereby the frame and rocker may be quickly lifted by the attendant should this be necessary. The face of the rocker is usually padded and covered with 100 paper as shown at 57, the ends of the padding being held by clamps 58.

In the operation of the machine it is found that owing to the small area of the belt in contact with the work at any one time the 105 action is uniform over the whole work, mainly because the dust and grit is carried out of the working area practically as fast as it is formed whereas with machines having a long area of belt contact the dust and grit accumulates between the surfaces as the belt advances, thereby progressively reducing the abrading action and hence giving defective and unsatisfactory results in that one side of the work is acted on more effectively than 110 the other.

Having thus described my invention, what I claim as new and desire to secure by Letters Patent, is:—

1. In an abrading machine of the type 120 described, a rocker having a curved surface for pressing the abrading material against the work, and means for oscillating said rocker to shift the position of the area of contact with the work.

2. In an abrading machine of the type 125 described a rocker having a curved surface for pressing the abrading material against the work, means for oscillating said rocker to shift the position of the area of contact with the work.

the work and means for varying the range of oscillation of the rocker.

3. In an abrading machine of the type described, an oscillatory rocker having a curved surface for pressing the abrading material against the work, means for oscillating the rocker and means for shifting the center of the arc of oscillation of the rocker.

4. In an abrading machine of the type described, an oscillatory rocker having a curved surface for pressing the abrading material against the work, means for oscillating the rocker, means for varying the range of oscillation and means for shifting the

15 center of the arc of oscillation of the rocker.

5. In an abrading machine the combination with the endless abrading belt and means for driving the same, of an oscillatory rocker having a curved surface for pressing the belt 20 against the work and manually operated means controlling the movement of the rocker.

6. In an abrading machine the combination with the endless abrading belt, means 25 for driving the same, and an oscillatory rocker having a curved surface for pressing the belt against the work, of arms on which said rocker is supported, means for simultaneously moving said arms to simultaneously depress one end and elevate the opposite end of the rocker and means for varying the range of movement of the arms.

7. In an abrading machine the combination with the endless abrading belt, means 35 for driving the same and an oscillatory rocker having a curved surface for pressing the belt against the work, of rock shafts, means for rocking said shafts in unison and crank arms mounted on said shafts in non parallel positions, for oscillating the rocker and whereby 40 one end of the rocker will be raised as the other is depressed.

8. In an abrading machine, the combination with the endless abrading belt, means 45 for driving the same and an oscillatory rocker having a curved surface for pressing the belt against the work, of rock shafts, crank arms on said shafts for oscillating the rocker and means for holding said crank arms in non- 50 parallel position whereby one end of the rocker will be raised as the other is depressed.

9. In an abrading machine, the combination with the endless abrading belt, means for driving the same, and an oscillatory 55 rocker having a curved surface for pressing the belt against the work, of rock shafts, crank arms on said rock shafts for operating the rocker and a connection between said crank arms of a length less than the distance

between the axes of the shafts, whereby one 60 end of the rocker will be elevated as the other end is depressed.

10. In an abrading machine, the combination with the endless abrading belt, means for driving the same and an oscillatory 65 rocker having a curved surface for pressing the belt against the work, of lever arms each pivotally mounted on a fixed axis at one end and pivotally connected with the rocker at the opposite end, rock shafts, crank arms on 70 said rock shafts coöperating with the lever arms for oscillating the rocker and means for rocking the rock shafts.

11. In an abrading machine the combination with the endless abrading belt, means 75 for driving the same and an oscillatory rocker having a curved surface for pressing the belt against the work, of a rocker operating mechanism embodying a slide, a link co-operating therewith, a radius bar to which 80 one end of the link is connected, an operating crank with which the opposite end of the link is connected and manually operated means for adjusting the link.

12. In an abrading machine the combination with the endless abrading belt, means for driving the same and an oscillatory rocker having a curved surface for pressing the belt against the work, of a rocker operating mechanism embodying a rock shaft, a 85 90 crank arm thereon connected with the rocker, a second crank arm on said shaft and means for angularly adjusting said crank arms with relation to each other for shifting the center of the arc of oscillation of the rocker. 95

13. In an abrading machine, the combination with the endless abrading belt, means for driving the same and an oscillatory rocker having a curved surface for pressing the belt against the work, of rock shafts having crank arms connected with the ends of the rocker, a hinged frame in which said rock shafts are journaled whereby the rocker may be lifted and means for rocking the rock shafts. 100

14. In an abrading machine the combination with the endless abrading belt, means for driving the same and an oscillatory rocker having a curved surface for pressing the belt against the work, of supports for the 110 rocker, universal joints connecting the rocker and its supports and means for oscillating the rocker to shift the field of contact between the belt and work.
